SWITZERLAND

NONOXIDIZING HEATING FURNACE

Application filed May 13, 1926, Serial No. 108,737, and in Germany May 30, 1925.

This invention relates to metal working and pertains particularly to apparatus for heat treatment of metal articles on which it is desired to preserve a surface finish.

5 The general object of the invention is the provision of apparatus whereby the articles may be heated in the presence of a non-oxidizing gas and loss of the gas prevented.

Another object is the provision of apparatus whereby the material may be maintained continuously in the presence of the gas during cooling as well as heating.

Still another object is the provision of apparatus whereby the infiltration of air is prevented.

A further object is the provision of apparatus whereby the heat of the gas may be utilized.

Other and further objects will be pointed out or indicated hereinafter or will be obvious to one skilled in the art upon an understanding of the invention.

In the drawing forming a part of this specification I show one form in which the invention may be embodied, but it is to be understood that the particular construction or arrangement herein shown and described is not to be construed as limiting the claim short of the true and most comprehensive scope of the invention in the art.

The drawing is a diagrammatic illustration, in the nature of a sectional elevation of a heating furnace construction with gas relief arrangement.

35 When finished metal articles, and in particular metal wire, are to be subjected to heat treatment and it is desired to prevent oxidation taking place, it is customary to fill the furnace with a more or less inert gas, usually 40 carbon dioxide. When the furnace is heated up, this gas expands and it is therefore necessary to provide an outlet through which the surplus gas may escape. Again, when the furnace is cooled there is a suction effect which

45 must be accommodated, and hitherto the practice has been to have the furnace permanently connected to a source supplying the gas. This method results in a large consumption of gas and increases the cost of the heat treatment.

50 In addition there is always the danger that

the supply of gas during the cooling-off period may be insufficient and allow air to be drawn into the muffle, thus oxidizing the charge.

According to the invention these disadvantages are avoided by connecting an expansion vessel or relief chamber to the furnace, which itself is practically gas tight. This vessel receives the surplus gas driven out when the furnace is heated and gives it up again during the cooling period. There is thus no necessity for the furnace to be permanently connected to the gas supply.

Such an arrangement may be very simply realized in practice. The example illustrated by the drawing shows a heat treatment furnace *a* provided with an electrical heating arrangement *g*, the outer casing *c* being made gas tight. The furnace is mounted in a brick-work pit *b* sunk in the floor, giving a clearance all round. The cover *d* which is provided with a liquid seal *f*, carries a siphon tube *e* leading from the interior of the furnace to a point near the bottom of the pit *b*, preferably in a depression *b'* which forms a trap or seal against atmospheric air when filled with a heavier gas above the end of the tube. A connection *h* is provided for supplying a desired gas to the furnace chamber.

The method of operation is as follows:—
80 The articles to be heat treated are introduced into the space *a* and carbon dioxide is then passed in until the furnace is completely filled; this may be determined by means of a lighted candle. After replacing the cover *d* 85 the heat treatment is commenced. As a result of expansion due to the heat, a large part of the carbon dioxide is forced out through the pipe *e*, is partially cooled in this pipe and thence passes into the pit *b* where it is completely cooled and collects. In this way part 90 of the heat in the gas is given up to the furnace, thus increasing the overall economy. On the heat treatment being completed, the charge is allowed to cool, and as the pressure 95 within the furnace falls, the carbon dioxide previously expelled is drawn back into the furnace through the tube *e*, which forms a free inlet for the gas. Thus induction of atmospheric air is avoided.

Instead of employing a pit as an expansion vessel for the gas, the furnace itself may be provided with a double casing, or to ensure still better cooling of the gas it may be led off into a separate pit. If the charge cannot be allowed to cool down in the furnace itself, owing to the high rate of production, it may be packed in boxes which are placed in the furnace and individually connected with the siphon tube leading to the relief receptacle. When it is required to cool the charge the boxes are removed from the furnace and connected by pipes to the relief receptacle.

What I claim is:—

15 In metal treating apparatus of the character described, means providing a vertically-disposed pit, a fluid-tight heating receptacle disposed in said pit and having such fit with respect thereto as to provide with the same 20 a storage chamber for fluid, and means providing a passage between said receptacle and said chamber and operating to permit of exchange flow of fluid between the same in either direction.

25 In testimony whereof I have hereunto subscribed my name at Zurich, Switzerland, on the 18th day of March, A. D. 1926.

GOTTLIEB KELLER.
